SIGNORS TO THE BRIDGEPORT HARDWARE MANUFACTURING CORPORATION, OF
BRIDGEPORT, CONNECTICUT, A CORPORATION OF CONNECTICUT.

VALVE LIFTER.

Application filed February 17, 1928. Serial No. 254,946.

This invention relates to valve lifting tools or tools for compressing valve springs in automobile engines to facilitate removal of the valve, and has for an object to provide an improved construction of tool which may be easily manipulated by one hand, and one in which the levers are so arranged as to secure sufficient leverage for easy manipulation.

It is also an object of the invention to make a construction which is simple and will be of rugged character so that it is not easily gotten out of order. It is also desirable to have a structure which will not occupy a large amount of space in a tool kit.

With the foregoing and other objects in view, we have devised the construction illustrated in the accompanying drawing forming a part of this specification. In this drawing,

Fig. 1 is a top plan view of our improved valve lifting tool.

Fig. 2 is a side elevation thereof showing the jaws in extended or separated position.

Fig. 3 is a side elevation of the forward end of the device showing the jaws in collapsed position.

Fig. 4 is a front elevation looking from the left of Fig. 2.

Fig. 5 is a detail of the mounting for the locking lever.

Fig. 6 is a plan view of one of the jaws removed.

Fig. 7 is a top plan view showing a slightly different arrangement of jaws, and

Fig. 8 is a side elevation of the jaws of Fig. 7.

The device comprises a pair of levers 10 and 11 pivoted together at 12. It will be noted these levers do not cross and have handles or grips 13 on one side of the pivot 12 and the extensions 14 and 15 of the levers 10 and 11 respectively on the other side of the pivot. As the levers do not cross these extensions are arranged so that as the handles are pressed together the free ends of these extensions separate or move away from each other.

Pivoted to the free ends of these extensions 14 and 15 are forked jaws 16 and 17 respectively, the pivots between the jaws and the extensions being shown at 18. It is preferred to form a boss 19 on the ends of these extensions 14 and 15 to give a longer bearing, and the body portion 20 of the jaw is notched, as shown at 21, to receive this boss

so that the pivot pin 18 is supported in 55 the jaw on both sides of the bearings 19 of the extensions to give a rigid and strong construction which will maintain the jaws in proper relative position. Extending rearwardly from the body portion on one side of 60 the notch of each jaw is an arm 22 and 23, and when in position the jaws are reversed so that the arm 22 of the upper jaw extends rearwardly at one side of the levers 10 and 11 while the arm 23 of the lower jaw extends 65 at the opposite sides of these levers. The free ends of these arms are pivoted together as shown at 24, preferably between the handles. It will now be apparent that as the handles of the levers are pressed together 70 the jaws 16 and 17 will be separated or moved apart and they will swing about the pivot 24.

Means is provided to hold or lock these jaws in any given position. For this purpose there is mounted on the pivot 12 a lever 25 having an upwardly extending arm 26 provided with a series of teeth or notches 27 in one edge cooperating with the lip 28 extending laterally from the arm 22 of the upper jaw. This lip may be integral with 75 the arm or it may be a separate plate 29 mounted in a recess in this arm and secured thereto by any suitable means, such as a screw 30. A coil spring 31 is seated in a 80 recess 32 in the lever 25 and has one end 33 extending into a notch in this lever and the other end 34 in a notch in one of the levers, as the lever 10. This spring tends to swing 85

the locking lever 25 to the left or counter-clockwise, as viewed in Figs. 2 and 5, and therefore, tends to hold the upwardly extending arm 26 against the lip 28. As the lip 26 is bent downwardly somewhat it will slide 90 freely over the teeth as the jaws are opened, but it will automatically engage a tooth to prevent movement in the opposite direction and will thus hold the jaws in separated position and will hold the valve spring compressed. The locking lever 25, however, has a rearwardly extending arm 35 provided with a finger piece 36 in a position where it is easily engaged by a finger or thumb of the operator to swing the locking lever to the right or clockwise and remove the upright arm 26 from the lip, permitting the jaws to collapse or move together.

In certain types of engines it is more con-

venient to slip the upper jaw between the turns of the coil spring than it is to insert it between the end of the spring and the abutment. We, therefore, so shape the upper jaw as to be easily inserted between these turns and to substantially conform to the shape thereof. As shown in Figs. 2, 3 and 4, the portion of the jaw on one side of the notch has its free end 37 bent slightly down-
wardly and the free end 38 on the other side bent slightly upwardly. This provides curved surfaces 39 and 40 curving in opposite directions on opposite sides of the notch which readily engage the curved turns of the spring on opposite sides of the valve stem.

It is also preferred for use with some engines that the jaws are not permitted to entirely collapse or come together. An adjustable stop pin 41 is thus provided which is tapped into the plate 29 and extends downwardly to engage the top edge of one of the levers, as for instance the extension 14, as shown in Fig. 3 to limit the closing movement of the jaws. This pin is provided with a slot 42 for a screw driver by means of which the pin may be adjusted to vary the distance between the jaws when closed.

In Figs. 7 and 8, we have shown a slightly different arrangement of the jaws. In these figures the jaws are forked the same as in the other form, but the lower jaw 43 is recessed somewhat on its top wall to receive the upper jaw 44, and the lower jaw extends forwardly at its free end beyond the free end of the upper jaw as indicated at 45. This extension is thickened somewhat so as to provide a shoulder 46 behind which the free end of the upper jaw is located when the jaws are collapsed as shown in Fig. 8. This facilitates insertion of the jaws in position between the abutment and the end of the spring or the spring washer because it involves in effect the insertion of a single element, which is the extension 45.

The above construction as will be apparent gives a compact arrangement of the various levers and gives sufficient leverage for comparatively easy manipulation of the device even against relatively heavy springs. The jaws swing about the pivot 24 between their rearwardly extending arms and this pivot in cooperation with the pivots 18 maintains the jaws in proper position.

Having thus set forth the nature of our invention, what we claim is:

1. In a valve lifting tool, a pair of levers pivoted together including handles on one side of the pivot and extensions on the opposite side of the pivot arranged to move away from each other as the handles are moved together, jaws pivoted to said extensions and each having an arm extending beyond the pivot between the levers, and a pivot connecting said arms.

2. In a valve lifting tool, a pair of levers pivoted together intermediate their ends including handles on one side of the pivot and extensions on the other side thereof, jaws pivoted to said extensions and each having an arm extending beyond the pivot between the levers, and a pivotal connection between said arms to connect said arms together.

3. In a valve lifting tool, a pair of levers pivoted together including handles on one side of the pivot and extensions on the opposite side of the pivot arranged to separate as the handles are moved together, a forked jaw pivoted to each extension and each jaw having an arm extending to the opposite side of the pivot between the levers, and a pivotal connection between said arms to connect them together and located between the handles.

4. In a valve lifting tool, a pair of levers pivoted together and including handles, a pair of forked jaws arranged to be operated by said levers, one of said jaws having the portions on opposite sides of the notch extending in opposite directions from the plane of the jaw so that they may project between the turns of a coiled spring on the opposite sides thereof.

5. In a valve lifting tool, a pair of levers pivoted together including handles on one side of the pivot and extensions on the opposite side of the pivot arranged to separate as the handles are moved together, forked jaws secured to said extensions and each having an arm extending beyond the pivot between the levers, a pivotal connection between the arms, a locking lever mounted on the pivot between the first mentioned levers and provided with a series of teeth, a lateral projection on one of the jaw members to engage said teeth, and a spring tending to hold the locking lever in engagement with said projection.

6. In a valve lifting tool, a pair of levers pivoted together including handles on one side of the pivot and extensions on the opposite side of the pivot arranged to separate as the handles are moved together, a jaw secured to each of said extensions, a locking lever mounted on the pivot between the first mentioned levers and provided with a series of teeth, a laterally extending lip on one of the jaw members arranged to engage said teeth to hold the jaws in spaced relation, a spring tending to hold the locking lever against the lip, and said locking lever having a finger piece for moving it in the opposite direction.

In testimony whereof we affix our signatures.

WILLIS F. HOBBS.
